DESIGN.

H. G. & W. R. DAWSON.

FIRE PLACE GRATE.

No. 17,402.

Patented June 21, 1887.

UNITED STATES PATENT OFFICE.

HENRY G. DAWSON AND WILLIAM R. DAWSON, OF CHICAGO, ILLINOIS.

DESIGN FOR A FIRE-PLACE GRATE.

SPECIFICATION forming part of Design No. 17,402, dated June 21, 1887.

Application filed April 23, 1887. Serial No. 235,914. Term of patent 7 years.

To all whom it may concern:

Be it known that we, HENRY G. DAWSON and WILLIAM R. DAWSON, of Chicago, in the State of Illinois, have invented and produced 5 a new and original Design for Grates for Fire-Places, of which the following is a specification, reference being had to the accompanying photographs, forming part thereof.

Figure 1 is a front view of the back and side 10 plates detached; and Fig. 2 is a front view of the grate complete, comprising the back and side plates shown in Fig. 1 and the front and crown piece.

The design consists in the raised figured 15 work on the face of the back and side plates and the lattice-work of the front and crown piece, and also in the several features as a whole.

A designates the side plates, and B the back 20 plate. The face *a* of these plates is roughened, so as to present the appearance of having been formed of a layer of small cells placed irregularly together. On this surface as a background are raised floral designs *b*. The top 25 of the back plate terminates in a figure, *b'*, made up of two convolute horn points, involving the stems of the floral work, and thence rising and uniting to form a body, which at once divides into a series of clavate branches 30 rising to the upper edge of the plate and terminating there to form a series of scallops along the upper edge, the center branch being the highest. The enlarging outer ends of the branches are provided with cross-ribs or 35 roughened surfaces.

The lattice work in front is composed of three bars, C, formed in a link, scroll shape, and having brass, nickel-plated, or black dots *c* at the end of each link, and the crown-piece D is formed of open figured work *d*. 40

What we claim as new, and desire to secure by Letters Patent, is—

1. In a design for a fire-place grate herein shown and described, the raised figure *b'*, consisting of two convolute horn points starting 45 a little below the center of the surface of the back plate, running together, and then spreading in clavate branches which cover the whole upper portion of the surface of said plate and terminate in a series of scallops along its upper edge. 50

2. The design for a fire-place grate herein shown and described, the same consisting in the side and back plates having their facing surfaces provided with the figured work shown 55 and described, and the front consisting of linked scroll-bars C, dots *c*, and scrolled crown-piece D.

3. In a design for a fire-place grate herein shown and described, the lattice work of the 60 front and crown piece, the same consisting of link scroll-bars C, dots *c*, and scrolled crown-piece D, shown and described.

HENRY G. DAWSON.
WILLIAM R. DAWSON.
